UNITED STATES PATENT OFFICE.

GUSTAF EM. JOHNSON, OF GRIDLEY, CALIFORNIA.

DESIGN FOR A LENS.

Application filed March 29, 1926. Serial No. 17,099. Term of patent 14 years.

To all whom it may concern:

Be it known that I, GUSTAF EM. JOHNSON, a citizen of the United States, residing at Gridley, in the county of Butte and State of California, have invented a new, original, and ornamental Design for a Lens, of which the following is a specification, reference being had to the accompanying drawing, forming part thereof, and in which—

Fig. 1 is a top plan view, and

Fig. 2 is a cross section on a considerably reduced scale.

The body of the device is of a reflective nature. The rings are colored red, white

and blue, and the flowers in the stars are formed in their natural colors. The rings, flowers and all other features are on the surface of the body only.

The lens, in different colors and sizes, can be used in tail or signal light casings of all kinds, such as those on motor and other vehicles; as a reflecting safety-lens to be carried on the back or front of a pedestrian, a bicycle or the like.

I claim:—

The ornamental design for a lens, as shown and described.

GUSTAF EM. JOHNSON.
